TILE GRINDING MACHINE

Joseph Mastrone, Bridgeport, Conn.

Application October 14, 1953, Serial No. 386,056

5 Claims. (Cl. 51—102)

1

This invention relates to portable machines for trimming and grinding the edges of tile components, particularly ceramic tiles and the like, used in building construction.

An object of the invention is to provide an improved portable grinding machine which is so constructed and arranged that edges of ceramic tiles may be easily, quickly and conveniently trimmed or dressed, either square or on a bevel, after the tile has been roughly cut to shape by a glazer's tool or other similar device.

Another object of the invention is to provide an improved portable grinding machine as above set forth, wherein the edges of ceramic and like tiles may be quickly and easily ground to have different shapes and contours.

A further object of the invention is to provide an improved grinding machine as above set forth in combination with dust collecting means, wherein there is maximum accessibility at the working surface of the wheel and effective dust collection, especially when working on small, thin or narrow strips of tile.

A still further object of the invention is to provide an improved tile grinding machine in accordance with the foregoing, wherein a minimum of adjustment is required when working with the various shapes and forms of tile normally encountered on a job.

A feature of the invention resides in the provision of a tile grinding machine of the type having a tiltable tile rest in combination with simplified and dependable gauge means, which means are movable and operative with said tile rest for all straight or tilted positions of the latter.

Yet another object of the invention is to provide an improved tile grinding machine in accordance with the foregoing, which is simple in construction, reliable in operation and economical to fabricate.

Other features and advantages will hereinafter appear.

In the accompanying drawings:

Figure 1 is a front elevational view of the improved tile grinding machine of the invention.

Fig. 2 is a side elevational view of the machine of Fig. 1.

Fig. 3 is a fragmentary side elevational view showing the gauge of the tile grinding machine in reversed position, for use with larger sizes of tiles.

As shown, the improved tile-grinding machine of this invention comprises a base 10 having an upright stand 11 provided with a horizontally-extending bearing sleeve 12 carrying a shaft or arbor 13. The bearing 12 receives lubrication from an oil cup 14 disposed on the top of the stand 11, and the shaft 13 carries at one end a drive pulley 15 and at the other end a grinding wheel 16.

2

In accordance with the present invention a novel and improved, combined tile rest, gauge and dust-collecting guard are adjustably mounted on the stand 11 to enable the edges of tiles used in building construction to be easily and quickly dressed or trimmed, or given various contours as desired. This novel assemblage comprises a supporting arm 17 pivotally mounted on a lower portion of the stand 11, said arm being carried by a lug 18 projecting laterally from the stand and having an extremity 19 at right angles to the lug, engaging the arm 17 and secured thereto by an Allen screw 20.

The supporting arm 17 extends forward and angularly upward from the lug 18 substantially in front of the grinding wheel 16, and at its upper extremity carries a tile rest 21 having the shape of a relatively long, narrow table with a flat surface 22. The tile rest 21 has a depending lug 23 receiving an Allen screw 24 by which it is pivotally mounted on the upper extremity of the supporting arm 17 for pivotal movement about a horizontal axis, such axis being parallel to the pivotal axis of the pivot screw 20.

The tile rest 21 is thus disposed immediately in front of the working face of the grinding wheel 16, and may be easily and quickly shifted either backward closer to the wheel or forward further from the wheel as desired, as by swinging the supporting arm 17. In addition, the tile rest 21 may be tilted by swinging it about the pivot screw 24, either forward and further from the wheel 16 or backward and closer to the wheel 16.

Further, in accordance with the invention, the tile rest 21 is provided with an advantageous gauge means which is movable with the tile rest and operative therewith regardless of the tile rest being in tilted or straight position. This gauge means comprises a slide including a bar 25 secured to the tile rest and extending forward therefrom, and a collar 26 slidable on the bar 25 and held in position by a wing-screw 27. The collar 26 carries a gauge member 28 having tile-engageable edges 29 and 30, the member 28 being offset from the collar 26 and spaced from the bar 25 to enable it to extend across the top of the tile rest 21 as shown by the dotted lines in Fig. 2, for the purpose of gauging and grinding thin or narrow strips of tile.

The tile gauge comprising the collar 26 and member 28 may be reversed on the bar 25, to enable larger pieces of tile to be guided, as illustrated in Fig. 3. The gauge means further constitutes a convenient method for tilting the tile rest 21, since raising or lowering of the bar 25 and gauge member 28 obviously will be accompanied by corresponding tilting of the tile rest 21, provided that the pivot screw 20 is maintained tight and not allowed to yield.

In accordance with this invention the support-

ing arm 17 mounts a dust guard 31 for movement therewith, said guard comprising a cylindrical shell 32 having ends 33 and 34, said shell and ends enclosing the grinding wheel 16. The end 33 of the guard has a horizontal slot 35 to clear the sleeve bearing 12, and the end 34 has a horizontal slot 36 opposite the slot 35, both said slots also providing clearance for tile workpieces supported on the tile rest 21.

In its lower portion the dust guard 31 has a discharge passage 37 connected with a dust bag 38 whereby the particles of tile ground off by the wheel 16 will be collected and may be disposed of.

The cylindrical shell 32 is provided with a mounting lug 39 in its front portion, having a slot 40 receiving an Allen screw 41 which is threaded into the supporting arm 17 intermediate the ends of the latter, and the dust guard 31 is thus adjustably mounted on the arm 17.

By the above organization the relative positions of the grinding wheel 16, tile rest 21 and dust guard 31 may be easily and conveniently varied to provide the proper spacing of the wheel and rest, together with the maximum collection of dust and maximum accessibility to the working face of the wheel.

In the operation of the device, tiles which have been previously roughly cut to size, as by a glazer's tool or the like, may have their edges trimmed smooth, or beveled, or given various contours as desired, by placing the tiles on the tile rest 21 and advancing the surfaces to be dressed against the working face of the wheel 16. If the dressing is to be along a straight edge, the gauge member 28 may be brought in engagement with the opposite edge of the tile, thereby to provide a guide for insuring uniformity of cut. Opposite bevels may be provided on edges of tiles by either tilting the tile rest 21 forward or backward, or else by turning upside down the tile on the tile rest while it is fixed in one tilted position.

Variations and modifications may be made within the scope of the claims and portions of the improvements may be used without others.

I claim:

1. A machine for grinding edges of tiles used in building construction, comprising an upright stand; a grinding wheel rotatably mounted on the stand for rotation about a horizontal axis; a supporting arm; means mounting the supporting arm on the stand at a point below the grinding wheel for pivotal movement about a horizontal axis; said arm normally extending forward and upward to position its upper end at a location in front of said wheel, and being swingable forward or backward about said mounting means; a tile rest; means mounting the tile rest on said upper end of the supporting arm for pivotal movement about a horizontal axis parallel with the axis of the first-named mounting means, said tile rest being positioned in front of the grinding wheel and being tiltable forward or backward independently of movement of the supporting arm; and a slideable gauge carried by said tile rest for engagement with an edge of a tile held on said rest, said gauge being adjustably movable toward and away from the tile rest and being adapted to guide a tile supported by said rest while another edge of the tile is being ground, said tile rest having a generally flat upper surface and said gauge comprising a slide structure secured to the tile rest and extending forward therefrom and further comprising a tile-engaging member carried by the slide structure and disposed above the plane of the top surface of

the tile rest, said slide structure enabling the tile-engaging member to be shifted across the top surface of the tile rest for the purpose of gauging narrow strips of tile.

5. The invention as defined in claim 1 in which the slide structure comprises a bar secured to the tile rest and a collar slidable on the bar and secured to the tile-engaging member, said collar and member being reversible on the bar to present a different gauging edge for engagement with the tile whereby a larger range of tile sizes may be accommodated on the tile rest.
10. 3. A machine for grinding edges of tiles used in building construction, comprising a stand; a grinding wheel rotatably mounted on the stand for rotation about a horizontal axis; a supporting arm; means mounting the supporting arm on the stand at a point below the grinding wheel, for pivotal movement about a horizontal axis, said arm normally extending forward and upward to a position wherein its upper end is located at the front of said wheel, and being adjustably movable either forward or backward with respect to said wheel; a tile rest; means 15 mounting the tile rest on said upper end of the supporting arm for pivotal movement about a horizontal axis parallel with the axis of the first-named mounting means, said tile rest being positioned in front of the grinding wheel and being 20 tiltable forward or backward independently of the adjusting movement of the supporting arm; a gauge carried by said tile rest for engagement with an edge of a tile held on said rest, said gauge being adjustably movable toward and away 25 from the tile rest and being adapted to guide a tile supported by said rest while another edge of the tile is being ground; and a dust collecting guard mounted on said supporting arm for adjustable movement therewith, said guard comprising an enclosure surrounding the grinding wheel, having an opening at its front adjacent the tile rest to expose the working surface of the wheel, the front portion of the guard moving further from the wheel as the supporting arm is 30 swung forward to move the tile rest further from the wheel, and moving closer to the wheel as the supporting arm is swung backward to bring the tile rest closer to the wheel, thereby to provide both for effective dust collection and accessibility 35 to a tile when the tile rest is close to the wheel for supporting narrow strips of tile.
30. 4. The invention as defined in claim 3 in which the guard has a cylindrical body and a mounting bracket on the front portion of said body, engaging said supporting arm.
35. 5. The invention as defined in claim 3 in which the dust collecting guard is adjustably secured to the supporting arm whereby it may be disposed closer to or further from the tile rest, enabling the spacing between the tile rest, dust 40 guard and working face of the wheel to be varied.
